United States Patent Office

Des. 174,972
Patented June 14, 1955

174,972

SIGN

Jack Ray Turner, Tucson, Ariz.

Application March 19, 1954, Serial No. 29,606

Term of patent 7 years

(Cl. D1—12)

Fig. 1

Fig. 2

Fig. 4

To all whom it may concern:

Be it known that I, Jack Ray Turner, a citizen of the United States, residing at Tucson, in the county of Pima and State of Arizona, have invented a new, original, and ornamental Design for a Sign, of which the following is a specification, reference being had to the accompanying drawings, forming a part hereof.

I claim:
The ornamental design for a sign, as shown.
